his Attorney.

UNITED STATES PATENT OFFICE.

GUSTAV VICTOR BENSON, OF CHICAGO, ILLINOIS.

INTERNAL-COMBUSTION ENGINE.

633.

Specification of Letters Patent.

Patented Nov. 2, 1909.

Application filed July 14, 1909. Serial No. 507,571.

To all whom it may concern:

It is known that I, GUSTAV V. BENSON, a citizen of the United States, residing at Chicago, county of Cook, and State of Illinois, invented certain new and useful Improvements in Internal-Combustion Engines, of which the following is a specification.

My invention relates to improvements in internal combustion engines, the object of the invention being to provide such a design and arrangement of the cylinders and valves that the latter will be operated by fluid pressure, thus obviating the use of cams, cam shafts and valve rods in an engine of this character.

Another object of my invention is to provide a simple structure in an engine which shall be economical of manufacture and of efficiency.

Other objects will appear hereinafter.

With these objects in view my invention consists in the novel construction and arrangement of parts which will be hereinafter fully described and more particularly pointed out in the appended claims.

My invention will be more readily understood by reference to the accompanying drawings forming a part of this specification and in which,

Figure 1 is a side elevation of my improved engine in its preferred form, Fig. 2 is a detail vertical section of a cylinder admission check valve, Fig. 3 is a vertical section taken on line $\alpha-\alpha$ of Fig. 1, and Fig. 4 is a central longitudinal section.

Referring now to the drawings, 1 designates the engine frame and 2 the crank shaft journal in the bearings 3 secured to said frame. A pulley or other means may be employed for transmitting power from shaft 2. Cross-heads 6 provided on the piston rods 7 are mounted to slide in the usual guides 8, the connecting rods 9 connecting said cross-heads with said crank shaft. The cylinders 10 and 12 are provided with stuffing-boxes 13 having metallic rings 14 which are covered with and separated by asbestos packing 15. The cylinders 10 and 12 are power expansion cylinders, and the cylinder 11 is a pumping cylinder piped to the explosion cylinders for the purpose of delivering explosive gas thereto. The cylinders are arranged parallel as shown and the pistons 16 operating therein are equipped with metallic spring packing rings 17.

The engine carbureter 18 is provided with the usual throttle valve and suitable operating rods 20 in connection therewith; said carbureter being connected with each end of the pumping cylinder 11 by means of the pipes 21 and 22, which are provided with ordinary check valves at the points 23 and 24 to prevent the combustible mixture or charge from returning to the carbureter. Thus, one carbureter serves for the complete engine, but it is understood that more than one carbureter may be used if deemed advisable in any particular engine of the same general construction. Ordinary jump spark plugs 24 are provided in the cylinder heads at both ends of each power cylinder, and any well known means for supplying current to said plugs may be employed.

Charge admission check valves 25 shown in detail in Fig. 3 are provided in the pipes 26, 27, 28 and 29 which connect the pumping cylinder 11 with the power cylinders 10 and 12. The valve-stem 30 of each admission valve 25 is preferably vertically disposed in order that the valve head 31 may seat properly and not be tilted by gravity. The chamber 32 is in the side of the valve nearest a power cylinder and the chamber 33 is in the side nearest the pumping cylinder. The helical spring 34 on the valve-stem 30 is adapted to maintain the valve head 31 in a normal seated position.

35 designates a removable plug.

The operation of the engine is as follows: When the piston 16 in the cylinder 10 is at one end of the stroke the piston 16 in the cylinder 12 is at the other, and the explosions take place simultaneously as indicated in the cylinders. An explosion occurs in each cylinder at both ends of the piston stroke, or, in other words, two explosions occur in each cylinder at one revolution of the crank shaft, four explosions occurring in the engine at one crank shaft revolution. The charge is drawn in to the pumping cylinder 11 by piston suction, first through pipe 21 then through the pipe 22, the check valves in these pipes preventing return flow of the charge. In the position of the pistons as shown in Fig. 4, the check valve at the point 23 is closed and the admission valves 25 in the pipes 27 and 28 are open, the pistons 16 having uncovered the exhaust ports 36. It is apparent that the admission valves 25 will not open until the pistons 16 have uncovered the exhaust ports 36 to reduce the pressure

within the cylinders to atmospheric pressure, thus allowing the high pressure of charge compression which obtains in the pumping cylinder 11 to open the valves 25 against the resistance of the springs 34. The charging gases will now flow into the cylinders following the spent gases as they pass out through the exhaust ports 36. On the return stroke of the pistons the exhaust ports are closed and the imprisoned charging gases in each cylinder are compressed and then ignited by the spark plugs 24 which are in connection with the usual timing apparatus. A charge will now be forced into the other ends of the cylinders through the pipes 26 and 29, the operation being similar at each end of the cylinders.

The important feature of the present invention is the automatic operation of the admission valves 25 whose action is dependent solely on unbalanced fluid pressure.

Various slight changes might be made in the general form and arrangement of parts described without departing from my invention, and hence I do not restrict myself to the precise details set forth, but consider myself at liberty to make such changes and alterations as fairly fall within the spirit and scope of the appended claims.

Having described my invention what I claim as new and desire to secure by Letters Patent is:

1. In an internal combustion engine, a frame and bearings secured thereto, a crank shaft journaled in said bearings, a charge pumping cylinder secured to said frame, a power explosion cylinder arranged on either side of said pumping cylinder, pistons operating in said cylinders and connected with said crank shaft, heads on each end of said cylinders, a carbureter and pipes provided with check valves leading therefrom to each end of said pumping cylinder, and pipes and admission check valves therein connecting the ends of each power cylinder with the ends of said pumping cylinder, substantially as described.

2. In an internal combustion engine, a crank shaft, a charge pumping cylinder and a power cylinder arranged on either side thereof, pistons operating in said cylinders and connected with said crank shaft by means of pistons and connecting rods, stuffing-boxes on one of the heads of each

cylinder having metallic packing rings surrounded with and separated by asbestos packing, a centrally disposed exhaust port in each power cylinder, means for drawing in and compressing a charge in each end of said pumping cylinder alternately, and admission check valves operating toward said power cylinders arranged in pipes connecting the ends of each power cylinder with the pumping cylinder, substantially as described.

3. In an internal combustion engine, a crank shaft, three crank pins lying in a plane passing through the crank shaft axis, one of said crank pins adjacent the end of the crank shaft being disposed opposite the other two, two power cylinders and a pumping cylinder arranged therebetween, pistons operating in said cylinders and connected with said crank pins, the pistons of said pumping cylinder and a power cylinder being connected to the two crank pins arranged on one side of the crank shaft axis, means of alternate charge admission into each end of said pumping cylinder, and power cylinder admission check valves arranged in pipes connecting the ends of each power cylinder with the pumping cylinder, the exhaust ports of said power cylinders being centrally arranged therein, substantially as described.

4. In an internal combustion engine, a crank shaft, a charge pumping cylinder and power cylinders arranged on opposite sides thereof and provided with centrally arranged exhaust ports, pistons operating in said cylinders connected with said crank shaft, means for charge admission into each end of said pumping cylinder, pipes connecting the ends of each power cylinder with the pumping cylinder, and check valves arranged in said pipes and opening toward said power cylinders, each check valve comprising a valve head and stem, the latter projecting through the valve casing and being surrounded by a helical spring adapted to maintain the valve in a normally closed position, substantially as described.

In testimony whereof I have signed my name to this specification in the presence of two subscribing witnesses.

GUSTAV VICTOR BENSON.
